TANGLEPROOF TWINE DISPENSER

Charles C. Rich, Bridgeport, Conn.

Application August 4, 1949, Serial No. 108,561

4 Claims. (Cl. 242—141)

1

This invention relates to holders operative to dispense twine or wrapping cord or other flexible line as it is uncoiled from a cop to be severed for use in a store or in the home, such as in tying up packages.

One object of the invention is to provide a holding and dispensing unit for a cop of twine which shall be proof against causing or permitting the twine to snarl or snag however carelessly or abruptly the same may be pulled away from the cop.

Another object is to provide a rotatable carrier for so holding a cop of twine that it may turn with unusual freedom for playing off the twine and yet prevent snarling and snagging of loose stretches or loops of the twine which tend to result from overrunning of the cop in a rotary direction when it is spun around in abruptly yanking off a length of the twine to be used.

A further object is to provide means for preventing such snarling and snagging which shall be equally effective both when the cop is full of twine and when the supply of twine is nearly depleted.

A further object is to provide a stand for a cop holding spindle or turntable so constructed that the turntable together with the cop may conveniently be removed from and restored to the stand.

A further object is to provide a cop holding turntable characterized by the above advantages on which cops of different sizes may be installed removably and interchangeably.

A still further object is to attain the stated features of operation when conventional cops are employed whose core tubes project beyond the winding of twine at one or both axial ends of the cop.

The foregoing and related objects and advantages of the invention will appear from the following description of a successful embodiment thereof having reference to the appended drawings wherein:

Fig. 1 is a perspective view of a twine dispensing stand incorporating a rotary cop holder embodying the present improvements.

Fig. 2 is a plan view of the unit of Fig. 1 taken partially in cross section on the horizontal planes 2—2 in Fig. 3, showing the twine of the cop nearly depleted.

Fig. 3 is a view taken in section on the vertical plane 3—3 in Fig. 2 looking in the direction of the arrows.

Fig. 4 is a fragmentary view taken in section on the plane 4—4 in Fig. 2 looking in the direction of the arrows.

2

Fig. 5 is a fragmentary view looking in the direction of arrow S in Fig. 2 showing a detail of the free end of the snarl preventing guard band.

5 Fig. 6 is a fragmentary plan view looking downward on Fig. 5.

Fig. 7 is a fragmentary sectional view of the structure in Fig. 3 showing a modified relationship of the guard ring to the turntable.

10 Fig. 8 is a sectional view like Fig. 3 showing a modified construction of turntable with associated guard ring arranged as in Fig. 7.

Fig. 9 is a fragmentary view of the structure in Fig. 7 showing parts in section on a central 15 vertical plane perpendicular to plane 3—3 in Fig. 2.

In Figs. 1 to 7, inclusive, the stationary stand of the holder is designated 12 and the rotary spindle or turntable that carries the cop is designated 13.

Stand 12 includes a stationary frame incorporating a mounting base 14 whose flanges 15 may be secured to a wooden counter 16 or the like by screws 17 and a frame strip 18 whose bent 25 length includes a bottom extension 19 secured to base 14 as by rivets 20 with a riser section 21 which is bent to form a horizontal bridge section 22 which again is bent to slope downward and form the thread guiding tongue 23 containing the guide hole 28 through which the twine or 30 cord 25 runs in being pulled off from the cop 24. A brace 29 may be provided at the upper bent corner of the riser section 21 secured by a rivet 26 to the riser section 21 and by a rivet 27 to the 35 bridge section 22 for adding rigidity to the frame strip in this region.

The cord or twine 25 in accordance with commercial practice is machine wound on a stiff hollow cardboard core 30. According to the 40 principles of this invention I seat the lower end of core 30 on a turntable 31 which in one form of the invention may be flat except for a raised conical center boss 32 bumped up from the sheet metal of the disc and perforated by a central hole 45 through which passes the vertical spindle 34. In other and preferred forms of the invention the turntable may be differently constructed as hereinafter described with reference to Figs. 8 and 9. In Figs. 1 to 7, a thrust shoulder 35 on spindle 50 34 fits the concavity in boss 32 so that disc 31 may seat on said boss and be fixed thereon in perpendicular relation to the axis of spindle 34.

Spindle shoulder 35 rests rotatably on the top of a stationary vertical bearing bushing 36 which is fast in the mounting base 14. The top end of spindle 34 is guided for free rotation in an elong-

gated slot 37 in the bridge section 22 of frame strip 18, the right end of slot 37 in Fig. 3 affording rotation permitting constraint for the top end of spindle 34 when the latter is truly vertical, and the left end of slot 37 giving enough clearance to permit the turntable 13, together with the cop 24 mounted thereon, to be lifted clear of bearing bushing 36 and canted into the broken line position in Fig. 3 whereupon they can be withdrawn in unison and completely from stand 12. Thus mounting base 14 and bridge section 22 comprise spaced apart cop straddling frame portions and the distance between them is spanned by the spindle 34.

For retaining the cop core 30 in centered position on the turntable, an axially expansive spring coil 40 is kept under tension between a thrust cup 41 loose on spindle 34 which bears downward against the top end of core 30 and a washer 32 loose on spindle 34 and held to a limit position therealong by the cotter pin 43 which in ordinary manner is removable from a crosswise hole through the spindle. Thus spring 40 presses the cop resiliently in a direction to urge it axially against the turntable.

The important snarl preventive features of my improved dispensing stand reside partly in structure that is stationary with frame 12 and partly in structure that is carried by the turntable 13.

The stationary part of the snarl preventing means involves line deflecting structure stationary with the frame distributed about and extending axially alongside the spindle 34 at sufficient radial distance therefrom to accommodate the turntable and cop inwardly of such line deflecting structure in freely turnable relation thereto. It includes a flat horizontal guard ring 46 supported in Fig. 3 just below and barely out of contact with the turntable disc 31 by means of a mounting saddle 47 continuous with the periphery of the ring. The down-turned end 48 of saddle 47 comprises a tongue which tucks snugly and removably into a slot provided between the riser section 21 of frame strip 18 and a socket forming loop 49 which may be welded fixedly on the riser section 21 of the frame strip. Upstanding from and continuous with the metal of guard ring 46 there are four guard posts 50 illustrative of spaced barriers which, in addition to riser section 21, limit the outward cast of loose strands of twine away from the cop 24 and deflect and constrain the twine to prevent its tangling. These posts together with guard ring 46 also effectively prevent the twine from escaping to a point below the bottom surface of turntable 13 at the outer edge of the latter and prevent the twine from snagging on any parts of the stand that are stationed beneath the turntable.

To prevent snarling of twine on the turntable itself, such as might be caused by wedging of the twine between the bottom of the cop and the top of turntable disc 31, there is provided a resilient contractile guard in the form of a thin band spring 53 which yieldably hugs the bottom end of the outside layer of twine on the cop regardless of how nearly full of twine or how nearly empty the core 30 may be. The anchored end 54 of spring 53 is looped about and free to swing on a stud 55 fixed in and upstanding from turntable disc 31. A nut 56 in threaded engagement with the top end of stud 55 retains spring end 54 on the stud with the assistance of top and bottom thrust washers 58. The inner end of band spring 53 is free and is rounded as well as flared outward as is best shown in Figs. 5 and 6 to assist

in smooth play-off of the twine from the bottom end of the cop when lightly clamped by the band spring.

In the operation of the form of the invention shown in Figs. 1 to 7, the twine or line of wrapping cord 25 will be pulled off from cop 24 through the guide hole 28 causing the cop 24 together with its turntable 13 to rotate to accommodate the play-off of the line. The line is normally pulled off from the cop in a direction to cause clockwise rotation of the cop with its turntable in Figs. 1, 2 and 6. This enables the windings of twine at the extreme bottom end of the cop to be played off smoothly and without danger of snagging on the free end 57 of spring guard 53, as shown in Figs. 5 and 6, even though these lower windings on the cop are always closely embraced by the yielding spring guard.

Nevertheless, Fig. 1 shows the presence of loose unwound convolutions of the twine surrounding the bottom portion of the cop, a condition wherein the twine 25 appears to extend from its guide hole 28 around the left side of the cop or spring guard 53 instead of the right side. Such condition might be occasioned by free overrunning of the cop after a vigorous yank is given to the line that would build up excessive whirling momentum in the cop in a clockwise rotary direction in Fig. 1, whereupon the overrunning of the cop would begin to wind back loosely upon itself the uncontrolled length of line that had once been pulled off through guide hole 28. This is a most severe test of the dispenser's ability to prevent accidental snarling and snagging of played-off stretches of the line because such action of the cop tends to cast loops of the line radially outward by centrifugal force. If uncontrolled, such loops would be certain to catch and snag on mechanical parts of the stand or turntable. In this invention the loops of line are effectively prevented from snagging or snarling by the close proximity of turntable disc 31 to its overlying stationary frame ring 46, and by the proximity of the bottom edge of guard band 53 to the turntable disc 31. These features of construction preclude the twine from being drawn in between band 53 and disc 31 as well as between the latter and its underlying frame ring 46.

As the supply of twine on cop 24 becomes depleted the band spring 53 will automatically contract spirally or act automatically to coil itself up from its expanded broken line position in Fig. 2 to its relatively contracted full line position. The guard band thereby continues to hug the bottom end portion of the cop snugly until all twine is removed from the cop.

A new cop may be installed on turntable 13 in place of the exhausted core 30 by merely lifting the turntable to its broken line position in Fig. 3 until the bottom end of spindle 34 is clear of the stand bearing 36. After this the top end of spindle 34 in unison with the turntable disc 31 may be inclined toward the left in the elongated bearing hole 37 in bridge section 22 of the frame strip so that the entire turntable is free to be separated from the stand 12. After this the empty core 30 may be removed by withdrawing cotter pin 43 from spindle 34 which frees spring 40 thrust washer 42 and thrust cup 41 all for removal endwise from spindle 34. This permits a new full cop to be installed in place of the empty core 30, after which the parts 40, 41 and 42 will be replaced and the cotter pin 43 restored. The turntable is reestablished on the stand by merely reversing the manipulation by which it was re-

moved involving no disassembly of any parts requiring tools.

If it be desired to remove the frame ring 46 from its retaining socket in loop 49, this can be done while turntable 13 is absent from the stand 12 by merely lifting the mounting tongue 48 of saddle 47 upward out of its socket to free it from the riser section 21 of frame strip 18.

In Fig. 7 the parts are so dimensioned and proportioned that the guard ring 46, as part of the line deflecting structure, closely flanks the upper face instead of the lower face of the peripheral border of the turntable. It is mounted by the same kind of tongue and socket construction comprising saddle 47 and socket 49 as is guard ring 46 of Figs. 1 to 6, inclusive. This enables the guard ring to be displaced upwardly away from its proximity to the turntable before the turntable 13 and its spindle 34 are removed from the frame bearings 36 and 37 as hereinbefore described.

In Figs. 8 and 9, the turntable 13' is equipped with a different expedient for preventing wedging or entrance of the twine between the bottom edge of the cop and the turntable. This involves substituting for the spring clamping band 53 an element 59 on the turntable having a funnel-shaped upper support face 61 against which the bottom outer edge of the cop 24 is always pressed downward by the tension of spring 40. The manner of anchorage of this spring and its resilient function is the same in Figs. 8 and 9 as in Fig. 3. In Fig. 8 the line deflecting structure 46', 47, 48, 49 and 50 may be constructed as shown in Fig. 7. The coaction of spring 40, funnel face 61, and the downwardly dished presser cap 41' also serves to maintain the cop 24 and its core 30 centralized with respect to and turnable in unison with spindle 34'.

Fig. 9 shows the manner in which the funnel shaped surface 61 of the turntable 13' insures the pressure of spring 40 always being borne by the extreme outer circular edge of the body of twine, cord or other line that is wound on the core 30 of the cop. The broken line positions 24' and 24" in Fig. 9 of an increasingly depleted cop show that this condition maintains throughout the withdrawal of line from the cop right up to the time the supply of twine is completely exhausted and the core 30 becomes bare. In other words, and contrary to Fig. 3, the core 30 will never abut against the turntable before all of the line wound on the cop is used up. Thus loose loops of line are always precluded from entering the space 62 between the lower end of the cop and the funnel-shaped top surface of the turntable by the perpetual pressure against the extreme outer edge of the wound cop however large or small in circumference the cop may be. Such pressure is assured by the action of spring 40 which also prevents the cop from "jumping up" away from face 61 which it might do in response to a yank on the line, particularly when the cop is nearly used up and light in weight.

To strengthen the sheet material of the element 59 of turntable 13' having the funnel-shaped surface 61, and to prevent loose line from entering beneath it, a disc 31', like disc 31 in Figs. 1 to 7, is fixed on spindle 34' and joined to the funnel element 59 of the turntable by a hollow cylindrical drum 63 which may be welded or otherwise permanently united with disc 31' and with the curled over circular top edge of the funnel element 59. This does away with sharp edges which can become nicked and with all

recesses or corners which could serve to catch and entangle loose coils of the line 25. The bearing washer 64 may also be welded to the turntable disc 13' and made of hard metal, if desired, for good wearing quality.

The distinctive features of construction which render my new dispenser tangle-proof and snag-proof as well as compact, economical to produce in quantities, and simple to manipulate, may be embodied in a variety of shapes and arrangements of structure differing from the exact illustrations herein given to explain the invention. The frame 19, 21, 22, 23 can be mounted on a wall so that the axis of spindle 34 is horizontal or inclined, instead of vertical. In such cases the term "turntable" used in the claims has its broad dictionary significance of a support having horizontal bearings to support a bar or spindle with which a reel can turn when unwinding rope. The appended claims are directed to and intended to cover all fair equivalents of the parts and assemblies herein disclosed which embody the invention and come within a broad interpretation of the terminology used in the claims.

This application is a continuation-in-part of my copending application, Serial No. 30,651, filed June 2, 1948, now abandoned.

I claim:

1. A tangle preventing cop holder for paying off from a freely rotatable cop a flexible line wound on a hollow core to form the cop, including in combination, a stationary frame comprising spaced apart cop straddling frame portions, bearings located respectively on said frame portions, a spindle axially spanning a distance between said frame portions long enough to extend axially through the hollow core of the cop, a turntable fixed on said spindle relatively near one of said bearings having one of its sides disposed to face one axial end of said cop, said spindle being rotatable in said bearings with sufficient freedom to permit said turntable to overrun rotary motion directly imparted thereto by line impelled rotation of said cop, a resilient device on said spindle relatively near the other of said bearings deriving thrust from said spindle and disposed to press resiliently against the other axial end of said cop in a direction to urge the cop axially against said side of the turntable with sufficient force to cause said cop to turn in unison with said turntable, and line deflecting and constraining structure including a ring-like platform closely flanking the peripheral border of said turntable and also including spaced barriers stationary with said frame distributed round about and extending axially alongside said spindle at sufficient radial distance therefrom to make room inside of said structure for said turntable and cop to overrun line impelled rotation of the latter.

2. A tangle preventing cop holder for paying off from a freely rotatable cop a flexible line wound on a hollow core to form the cop, including in combination, a stationary frame comprising spaced apart cop straddling frame portions, bearings located respectively on said frame portions, a spindle axially spanning a distance between said frame portions long enough to extend axially through the hollow core of the cop, a turntable fixed on said spindle relatively near one of said bearings having one of its sides disposed to face one axial end of said cop, said spindle being rotatable in said bearings with sufficient freedom to permit said turntable to overrun rotary motion directly imparted thereto by line

impelled rotation of said cop, a resilient device on said spindle relatively near the other of said bearings deriving thrust from said spindle and disposed to press resiliently against the other axial end of said cop in a direction to urge the cop axially against said side of the turntable with sufficient force to cause said cop to turn in unison with said turntable, and line deflecting and constraining structure including spaced barriers stationary with said frame distributed round about and extending axially alongside said spindle at sufficient radial distance therefrom to make room inside of said structure for said turntable and cop to overrun line impelled rotation of the latter and also including a ring-like platform disposed in a position closely flanking said side of said turntable with cooperative mounting devices in part on said stationary frame and in part on said platform interengaging in a manner to support said platform fixedly and displaceably in its said position, whereby displacement of said platform may precede and facilitate removal of said spindle from said frame bearings.

3. A tangle preventing cop holder for paying off from a freely rotatable cop a flexible line wound on a hollow core to form the cop, including in combination, a stationary frame comprising spaced apart cop straddling frame portions, bearings located respectively on said frame portions, a spindle axially spanning a distance between said frame portions long enough to extend axially through the hollow core of the cop, a turntable fixed on said spindle relatively near one of said bearings having one of its sides disposed to face one axial end of said cop, the one of said bearings most remote from said turntable being elongated crosswise the axis of said spindle sufficiently to permit said spindle to be tipped in a manner to facilitate removal thereof from said bearings and said spindle being rotatable in said bearings with sufficient freedom to permit said turntable to overrun rotary motion directly imparted thereto by line impelled rotation of said cop, a resilient device on said spindle relatively near the other of said bearings deriving thrust from said spindle and disposed to press resiliently against the other axial end of said cop in a direction to urge the cop axially against said side of the turntable with sufficient force to cause said cop to turn in unison with said turntable, and line deflecting and constraining structure including spaced barriers stationary with said frame distributed round about and extending axially alongside said spindle at sufficient radial distance therefrom to make room inside of said structure for said turntable and cop to overrun line impelled rotation of the latter.

4. A tangle preventing cop holder for paying

off from a freely rotatable cop a flexible line wound on a hollow core to form the cop, including in combination, a stationary frame comprising spaced apart cop straddling frame portions, bearings located respectively on said frame portions, a spindle axially spanning a distance between said frame portions long enough to extend axially through the hollow core of the cop, a turntable fixed on said spindle relatively near one of said bearings having one of its sides disposed to face one axial end of said cop, said spindle being rotatable in said bearings with sufficient freedom to permit said turntable to overrun rotary motion directly imparted thereto by line impelled rotation of said cop, a resilient device on said spindle relatively near the other of said bearings deriving thrust from said spindle and disposed to press resiliently against the other axial end of said cop in a direction to urge the cop axially against said side of the turntable with sufficient force to cause said cop to turn in unison with said turntable, and line deflecting and constraining structure including spaced barriers stationary with said frame distributed round about and extending axially alongside said spindle at sufficient radial distance therefrom to make room inside of said structure for said turntable and cop to overrun line impelled rotation of the latter, together with a looped leaf spring having one end pivotally anchored to said turntable and having its resilient length disposed to surround and yieldingly press against the perimeter of said cop while an edge of said leaf spring is sufficiently close to said turntable to prevent line drawn off the cop from entering therebetween.
